MARINE TYPE NONMETALLIC BEARING

William M. Fountain, Palo Alto, and
Herbert Pierce, Saratoga, Calif.

Application March 27, 1945, Serial No. 585,086

5 Claims. (Cl. 115—34)

1

The present invention relates to improvements in a marine type non-metallic bearing, and it consists of combinations, constructions and arrangements hereinafter described and claimed.

An object of our invention is to provide a marine type non-metallic bearing for propeller shafts which will permit the take-up of either inner or outer bearings while the boat still remains in the water. This obviates the necessity of running the boat onto the shore or into dry-dock in order to repack the bearings. The device can be applied to boats of various sizes.

A further object of our invention is to provide a device of the type described in which the water floating the boat is used as the lubricating means for the bearings. The device is simple in construction and durable and efficient for the purpose intended.

Other objects and advantages will appear in the following specification, and the novel features of the device will be particularly pointed out in the appended claims.

Our invention is illustrated in the accompanying drawing forming a part of this application, in which:

Figure 1 is a side elevation of the device shown operatively applied to the boat; and

Figure 2 is a longitudinal section through the device.

While we have shown only the preferred form of our invention, it should be understood that various changes or modifications may be made within the scope of the appended claims without departing from the spirit and scope of the invention.

In carrying out our invention we make use of a boat indicated generally at A. This boat has a hull 1 and a stern 2. Our marine type bearing indicated generally at B comprises a cylinder 3 that extends through an opening 4 in the stern 2 of the boat and has a flange 5 that is designed to be secured to the outer surface of the stern by screws 6 or other suitable fastening means. The flange is preferably integral with the cylinder, as shown in Figure 2.

The rear of the cylinder 3 is threaded internally at 7 for receiving an inner gland 8 that is exteriorly threaded so as to be screwed against a plurality of split packing rings 9 forming the outer bearing. The packing rings bear against an inner disc 10 which is held in place by a set screw 11. The inner gland 8 is secured to an outer gland 12 by screws 13 or other suitable fastening means. The outer gland 12 has projections 14 that are designed to be engaged by a spanner 55

2

wrench, not shown, for rotating the outer and inner glands as a unit for compressing the packing rings 9.

Figure 1 shows how the outer gland 12 is held against accidental rotation by locking bolts 15. These bolts are pivotally mounted in lugs 16 that are integral with the cylinder 3 and flange 5. The outer gland 12 has pairs of lugs 17 designed to receive the bolts 15. After the gland 12 has been tightened to the desired extent, the pairs of lugs 17 are brought into alignment with the lugs 16 and then the bolts 15 are swung so as to be received in the lugs 17. Nuts 18 are now tightened against the lugs 17 and will hold the outer and inner glands from rotating.

The disc 10 and the inner gland 8 have openings 19 and 20 for rotatably receiving the propeller shaft C of the boat. Figure 1 shows the propeller shaft projecting beyond the outer packing gland 12 and further shows a propeller D keyed to the shaft and held in place by a nut 21.

The forward end of the propeller shaft C projects through an opening 22 in a disc 23 and through an opening 24 in a forward packing gland 25. The gland 25 is exteriorly threaded at 26 and is designed to be screwed into an interiorly threaded portion 27 provided in the forward end of the cylinder 3. Packing rings 28 form the inner bearing and are compressed between the disc 23 and the forward packing gland 25. A set screw 29 secures the disc in the cylinder.

The propeller shaft C has its forward end rotatably received in a double thrust bearing indicated generally at E. It will be seen from Figure 2 that the propeller shaft C is threaded at 30 for receiving a nut 31. The double thrust bearing E has a housing 32 for receiving rollers 33 of the double thrust bearing E. The nut 31 holds a cap 34 down upon the double thrust bearing E so as to keep the bearing within the housing 32. The propeller shaft C is reduced in diameter at 35 and the reduced portion passes through a thrust bearing holder F. The shaft C is threaded at 36 and receives a nut 37 that secures a cap or holder 38 against the thrust bearing holder F.

Figure 2 also shows the propeller shaft C still further reduced in diameter at 39 and keyed to a coupling member 40. The coupling is held in place by a nut 41 and is adapted to be secured to a second coupling member, not shown, which may be directly connected to the engine shaft or other source of power. A rotation of the coupling member 40 will rotate the shaft which in turn will rotate the propeller in the water indicated at G. A thrust bearing bracket H, see Figure 1, has

a cradle portion 42 extending from the cylinder 3 to the housing 32. The bracket has a saddle portion 43 with lugs 44 for receiving the cylinder 3 and a cap 45 is designed to be placed over the cylinder and be secured to the saddle lugs by bolts 46. In this manner the bracket is rigidly secured to the cylinder 3. The bracket has a second saddle portion 47 that has lugs 48 for receiving the housing 32 and a cap 49 fitting over the housing 32 is secured to the lugs 48 by bolts 50. The housing 32 together with the double thrust bearing E and the thrust bearing holder F are held in proper position by the bracket.

Both Figures 1 and 2 show a sea water pressure tube J extending from a central opening 51 in the cylinder 3 and passing through an opening 52 in the hull 1 and facing forwardly as shown in Figure 1. As the boat moves forwardly in the water, the water will enter the tube J and flow into the interior of the cylinder 3 where it will enter the outer and inner bearings 9 and 28 for acting as a lubricant between the rings and the propeller shaft. No oil is needed for lubrication purposes.

From the foregoing description of the various parts of the device, the operation thereof may be readily understood.

The propeller shaft operates in the usual manner for rotating the propeller. The inner bearing 28 or the outer bearing 9 may be taken up to compensate for wear while the ship remains in the water. The take-up of the bearing 28 is accomplished by rotating the gland 25 while the take-up on outer bearing 9 is accomplished by rotating the gland 12. A spanner wrench is used for rotating the glands. It is possible to loosen the bolts 15 and swing them free of the lugs 17 and then rotate the gland 12, all of this operation being performed while the boat remains in the water.

The shaft C may be removed from the cylinder 3 and this is accomplished by unscrewing the nuts 41, 37 and 31 to free the shaft from the coupling member 40 and the bearings E and F. The shaft may then be pulled free of the cylinder. The packing rings forming the outer and inner bearings 9 and 28 may be made of rubber or synthetic rubber. The rings are split so that they can be temporarily opened to encircle the shaft without the necessity of removing the shaft from the cylinder. Any plastic material that will function as a bearing ring will suffice. The bearings 9 and 28 are lubricated with the same water the ship floats in.

The double thrust bearing E will take up the propeller thrust when the ship is proceeding in either a forward or a reverse direction. The double thrust bearing E can be inspected by the removal of the cap or holder 34 and the bracket H. There is no need for removing the propeller shaft for this inspection. The coupling flange 40 can be removed by dismounting the nut 41 and sliding the coupling off on keyway 39a.

The water for lubricating the bearings 9 and 28 is admitted into the cylinder 3 through the tube J. The bearings are lubricated under pressure with the same water that floats the ship or boat. Any leakage of water that might develop through the gland 12 will be balanced by the water pressure entering the center of the cylinder 3 through the tube J.

Our bearing is designed to be used in place of the commonly used hard or metallic bearings such as lignumvitae or similar hardwoods, brass or bronzes, or other metallic materials. The bear-

ings can be repacked without removing the ship from the water because the glands can be unscrewed from the cylinder 3 and then the new rings slipped over the propeller shaft and moved into place. If the propeller shaft is too long, the cylinder 3 can have an intermediate support, not shown. The threads for the gland 8 are shielded from the water by the outer gland 12.

We claim:

1. A marine-type non-metallic bearing comprising a tubular casing adapted to extend through the stern of a ship at a point below the water line, a propeller shaft extending through the casing, the shaft axis coinciding with the casing axis, transversely-extending partitions spaced a predetermined distance from each end of the casing and being spaced from each other to define a chamber therebetween within the casing, said partitions having central openings larger in diameter than the shaft diameter, the shaft extending through said openings but having clearance with the partitions, a plurality of non-metallic packing and bearing rings encircling the shaft and being disposed between the partitions and the casing ends for providing inboard and outboard bearings constituting the sole supports within the casing for the shaft, a packing gland for each casing end for taking up wear in each bearing, the packing glands having central openings larger in diameter than the shaft diameter so as to receive the shaft with clearance, the outboard gland admitting water to the outboard bearing from the body of water floating the ship, and means for conveying water into the chamber for water-lubricating the bearings.

2. A marine-type non-metallic bearing comprising a tubular casing adapted to extend through the stern of a ship at a point below the water line, a propeller shaft extending through the casing, the shaft axis coinciding with the casing axis, transversely-extending partitions spaced a predetermined distance from each end of the casing and being spaced from each other to define a chamber therebetween within the casing, said partitions having central openings larger in diameter than the shaft diameter, the shaft extending through said openings but having clearance with the partitions, a plurality of non-metallic packing and bearing rings encircling the shaft and being disposed between the partitions and the casing ends for providing inboard and outboard bearings constituting the sole supports within the casing for the shaft, a packing gland for each casing end for taking up wear in each bearing, the packing glands having central openings larger in diameter than the shaft diameter so as to receive the shaft with clearance, the outboard gland admitting water to the outboard bearing from the body of water floating the ship, and a tube communicating with the chamber between the partitions, said tube projecting through the ship's hull and having its lower end facing ahead for conveying water under pressure to the casing chamber and to the bearings.

3. In a marine propeller shaft support, a propeller shaft casing adapted to extend through the stern of a ship at a point below the water line, the casing being internally threaded at its outboard end, an inner packing gland threaded for engagement with the casing threads, said inner gland being rotatable with respect to the casing, an outer packing gland secured to the inner one and including a sleeve that slidably and rotatably receives the outboard casing end, the sleeve shielding the threads of the casing and inner

gland against entrance of water, and means for locking said outer and inner glands against accidental rotation, said locking means being releasable for permitting the glands to be adjusted while the ship is in the water.

4. In a marine propeller shaft support, a propeller shaft casing adapted to extend through the stern of a ship at a point below the water line and having a propeller shaft mounted therein and projecting from the forward end of the casing, a double-thrust bearing for the shaft portion projecting beyond the forward casing end for taking up the propeller shaft thrust whether the ship is moving ahead or astern, thrust bearing holders disposed on the shaft, a housing for the thrust bearing, and a bracket extending between the housing and casing designed to support the housing and to transmit thrust from the latter to the casing, said bracket being removably connected to the casing and housing, whereby the bracket can be removed from the housing for permitting inspection of the double-thrust bearing without the necessity of removing the shaft from the casing.

5. In a marine propeller shaft support, a propeller shaft casing adapted to extend through the stern of a ship at a point below the water line and having a propeller shaft mounted therein and projecting from the forward end of the cas-

15

5 whether the ship is moving ahead or astern, a housing for the thrust bearing, and a bracket secured to the casing and housing designed to support the housing and transmit thrust from the latter to the casing, the bracket having a sump therein arranged to receive liquid leaking out of the packing gland or thrust bearing housing and preventing the liquid from dropping into the bottom of the boat.

ing, a packing gland disposed at the forward end of the casing, a double-thrust bearing for the shaft portion projecting beyond the forward casing end for taking up the propeller shaft thrust
